UNITED STATES PATENT OFFICE.

THOMSON HOWELL, OF NEWARK, NEW JERSEY.

CARBURETER.

No. 901,345.

Specification of Letters Patent.

Patented Oct. 20, 1908.

Application filed March 5, 1908. Serial No. 419,318.

To all whom it may concern:

Be it known that I, THOMSON HOWELL, citizen of the United States, residing at Newark, in the county of Essex and State of New Jersey, have invented certain new and useful Improvements in Carbureters; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

15 The present invention relates, generally, to improvements in carbureters for gas engines; and the present invention has for its principal objects to provide a novel and simply constructed apparatus or device in which a perfect mixture of gasoline with air is caused to produce the explosive gas which is to be exploded in the cylinder of the gas engine.

The invention has for its further object 25 to provide in connection with the gasoline intake, a novel means for regulating the amount of gasoline permitted to enter the carbureting chamber, to be mixed therein with the air to form the explosive gas, this 30 said regulating means being automatic in its action and being controlled by the needs of the engine.

Other objects of this invention not at this time more particularly set forth will be 35 clearly evident from the following detailed description of the same.

With the various objects of the present invention in view, the same consists, primarily, in the novel carbureter for gas-engines hereinafter more fully set forth; and, furthermore, this invention consists in the general arrangements and combinations of the various devices and parts, as well as in the details of the construction of the same, all of 45 which will be presently more fully described, and then finally embodied in the clauses of the claims which are appended to and which form an essential part of this specification.

The invention is clearly illustrated in the 50 accompanying drawings, in which:—

Figure 1 is a longitudinal vertical section of the novel carbureter. Fig. 2 is a vertical cross-section taken on line 2—2 in said Fig. 1, and looking in the direction of the 55 arrow x. Fig. 3 is a detail longitudinal ver-

tical section, similar to Fig. 1, illustrating more particularly the gasoline-intake and regulating means connected therewith, when the same is in operation and is admitting the gasoline into the carbureting chamber. 60

Similar characters of reference are employed in all of the above described views, to indicate corresponding parts.

Referring now to the several figures of the drawings, the reference-character 1 indicates 65 a complete carbureter, illustrating one form of the present invention, the same consisting, essentially, of a main shell or body 2, provided with a closed bottom 3, and is made with an open top, having a screw-thread 4 70 on its outer surface for attaching the same in operative relation with the gas-engine apparatus. The said main shell or body 2 is further provided with a forwardly extending member or portion 5, the same being 75 formed with a hole or opening 6, the said forwardly extending member or portion 5 being further provided with an annular flange 7.

A tubular member or shell 8, provided at 80 one end with an annular flange 9, is connected with said main shell or body 2, by placing the said annular flange 9 in alignment with the annular flange 7 of the forwardly extending member or portion 5 of 85 said main shell or body 2, and securing the same together by means of screws or bolts 10, or any other suitable fastening means, which are passed through holes in the said flanges 7 and 9, substantially as shown. This 90 said tubular member or shell 8 provides a carbureting chamber 11 into which the air is drawn or sucked, through the open free end thereof, preparatory to mixing the gasoline therewith. The said tubular member or 95 shell 8 is furthermore provided in its interior with suitably disposed arms formed with a centrally disposed hub 12, said hub 12 and the arms 13 being preferably formed integrally with the said tubular member or 100 shell 8. The hub 12 is provided with a centrally disposed hole or opening supplied with the interior screw-threads 14. Secured in this hub 12 by means of its screw-threaded end 15 is a gasoline intake-pipe and valve- 105 mechanism 16, which comprises a tubular opening or duct 17 extending longitudinally into the said intake-pipe 16, said opening or duct 17 terminating in a cone-shaped valve-seat 18. Extending from this seat 18 is another 110

tubular opening or duct 19 of smaller diameter in cross-section than that of the opening or duct 17, this said opening or duct 19 extending longitudinally through and to the free end of the said intake-pipe 16. The free end of this said intake-pipe 16 is provided with a screw-thread 20, by means of which it can be connected with a gasoline supply-pipe, or the like, leading from a gasoline tank or other source of supply. The said intake-pipe 16 is further provided with a plurality of laterally extending holes or perforations 21, the same leading into and connecting with the opening or duct 17.

15 Concentric with the said intake-pipe 16 is a tubular member 22 which is provided at one end and upon its opposite sides with longitudinally disposed slots 23, said slots being arranged over and registering with the outer ends of the said holes or perforations 21 of the intake-pipe 16. This said tubular member 22, when properly adjusted in its operative relation as above described, may be secured in place by means of the 20 set-screw 24 which is provided with the operating finger or thumb-piece 25; or, the said parts or members may be otherwise secured, if desired. The said tubular member or shell 8 is further provided in its interior with 25 another centrally disposed hub 26 which is formed with a hole or opening 27, this hub being supported by suitable arms 28 which are preferably formed integral with the said tubular member or shell 8.

30 Slidably arranged in the hole or opening 27 of the hub 26 is the valve-stem 29, of what is ordinarily termed a needle-valve, said stem extending into and being slidably arranged in the tubular opening or duct 17 35 of the intake-pipe 16. The said valve-stem is provided upon its free end with a cone-shaped portion 30 adapted to normally be seated upon the valve-seat 18, so as to close the tubular opening or duct 19. The valve-stem 29 is furthermore adapted to close the 40 said plurality of laterally extending holes or perforations 21 against the passage of the gasoline therethrough.

A disk 31, preferably provided with a hub 45 or boss 32, is suitably secured upon the end of the valve-stem 29, preferably, by means of a pin 33.

The said main shell or body 2 is provided with a boss or enlargement 34 having a 50 hole therein which is provided with a screw-thread 35, and the reference-character 36 indicates an adjusting screw which penetrates into the interior of the said main shell or body 2. Secured upon the inner end of 55 said adjusting screw 36 is a flanged nut or collar 37, the same being preferably secured by means of the pin 38, but any other suitable means of fastening may be employed. Arranged upon this collar or nut 37, so as 60 to engage with the flange thereof, is one end

of a spring, as 39, the other end of said spring engaging with the hub 32 of the disk 31. The purpose of the spring 39 is to normally keep the cone-shaped end 30 of the valve-stem 29 seated upon the seat 18 of the 65 gasoline intake-pipe 16; and, at the same time causing said stem to maintain a closed relation of said laterally extending holes or perforations 21, as will be clearly evident. The outer end-portion of the adjusting screw 70 75 36 is provided with an operating finger or thumb-piece 40, by means of which in turning the adjusting screw 36, the said screw can be made to increase or decrease the tension of the spring 39, as will be clearly understood from an inspection of Fig. 1 of the drawings. When a proper adjustment of the tension of the spring 39 has been secured, there is provided in connection with the adjusting screw 36, a lock-nut 41 which 80 is screwed upon the shank of the adjusting screw and against the outer face of the boss 34 to lock the adjusting screw in its adjusted position. Arranged in the upper portion of the said main shell or body 2 is a shaft or 85 spindle 42, said spindle being suitably journaled in the walls of said main shell or body 2. Said shaft or spindle is also provided at one end with an upwardly extending lever or actuating arm 43, and rigidly secured 90 upon the shaft or spindle, within the main shell or body 2, is a disk 44, the same forming a regulating-valve or throttle for controlling the amount of gas to be drawn from the carbureting chamber.

Having thus described the construction and essential parts of the novel carbureter embodying the principles of this invention, it now remains to describe the same as it operates to mix the gasoline and air to form 105 the gas to be supplied to the gas engine, and the novel means of regulating such admixture.

In the ordinary gas-engines the "mixture" of gasoline and air is drawn into the 110 cylinder of the engine by the suction of the moving piston.

In the present invention, when the moving piston in the engine-cylinder begins this sucking action, the suction which is created in 115 the interior of the main shell or body 2 causes the disk 31 to be drawn inwardly against the tension of the spring 39. This action causes the cone-shaped end 30 of the valve stem 29 to be withdrawn from the seat 18, and allows the tubular opening or duct 19 to be opened, and thereby permits the gasoline to flow into the tubular opening or duct 17. The valve stem 29, as it is drawn outwardly, also exposes one or more of the 120 laterally extending holes or perforations 21 and permits the gasoline to pass therethrough and through the narrow slots 23, from whence it is sprayed into the carbureting chamber 11, in which the gasoline is 125 130

mixed with the air which is sucked into the interior of the main shell or body 2 and thence into the engine cylinder.

The disk 44 which forms a throttle or regulating valve may be turned or adjusted so as to increase or decrease the power of the suction, as will be evident. The stronger the suction, the farther out the disk 31 and the valve-stem 29 will be drawn, and consequently a greater number of the holes or perforations 21 are exposed to the passage of the gasolene, which results, as will be clearly evident, in an increased percentage of gasolene being mixed with the air and a heavier or more highly charged explosive mixture will be the result.

It will thus be clearly understood, that the present invention provides an extremely simple, but a very effectively operating carbureting device in which the strength of the gaseous mixture is automatically regulated according to the needs of the engine.

The device has practically few parts, and these of very simple construction and operation, hence the carbureter is not likely to get out of order or cause any undue trouble or annoyance.

I am aware that changes may be made in the various arrangements and combinations of parts, as well as in the details of the construction of the same without departing from the scope of the present invention, as defined in the appended claims. Hence, I do not limit my invention to the exact arrangements and combinations of the devices and parts, as illustrated in the accompanying drawings, and as described in the accompanying specification, nor do I confine myself to the exact details of the construction of the said parts.

I claim:

1. A carbureter for explosive gas-engines comprising a main tubular body provided with an air-intake, and an outlet, a pair of arms extending diametrically across the interior of said main body, one of the said sets of arms being provided with an internally screw-threaded hub, and the other set of said arms having a hub formed with a hole, providing a guide, a tubular gasolene-conveyer extending into the mixing chamber of said body and being provided with a screw-threaded portion screwed into said screw-threaded hub, said conveyer being provided with a plurality of perforations or holes, and a valve-seat within said conveyer, a spindle movably arranged in the hole of said one set of arms, said spindle having a portion movably arranged within said conveyer and being provided with a cone-shaped end adapted to normally rest upon said valve-seat, and means connected with said spindle adapted to be actuated by suction for removing said cone-shaped end from the valve-seat and thereby opening one or more

of said perforations of the gasolene-conveyer.

2. A carbureter for explosive gas-engines comprising a main tubular body provided with an air-intake, and an outlet, a pair of arms extending diametrically across the interior of said main body, one of the said sets of arms being provided with an internally screw-threaded hub, and the other set of said arms having a hub formed with a hole, 70 providing a guide, a tubular gasolene-conveyer extending into the mixing chamber of said body and being provided with a screw-threaded portion screwed into said screw-threaded hub, said conveyer being provided 75 with a plurality of perforations or holes, and a valve-seat within said conveyer, a spindle movably arranged in the hole of said one set of arms, said spindle having a portion 80 movably arranged within said conveyer and being provided with a cone-shaped end adapted to normally rest upon said valve-seat, and a spring-controlled means connected with said spindle adapted to be actuated by suction for removing said cone-shaped end from the valve-seat and thereby 85 opening one or more of said perforations of the gasolene-conveyer.

3. A carbureter for explosive gas-engines comprising a main tubular body provided 95 with an air-intake, and an outlet, a pair of arms extending diametrically across the interior of said main body, one of the said sets of arms being provided with an internally screw-threaded hub, and the other set 100 of said arms having a hub formed with a hole, providing a guide, a tubular gasolene-conveyer extending into the mixing chamber of said body and being provided with a screw-threaded portion screwed into said 105 screw-threaded hub, said conveyer being provided with a plurality of perforations or holes, and a valve-seat within said conveyer, a spindle movably arranged in the hole of said one set of arms, said spindle having a 110 portion movably arranged within said conveyer and being provided with a cone-shaped end adapted to normally rest upon said valve-seat, and means connected with said spindle adapted to be actuated by suction 115 for removing said cone-shaped end from the valve-seat and thereby opening one or more of said perforations of the gasolene-conveyer, consisting of a disk arranged upon said spindle, an adjusting screw connected with said 120 main body, and a spring between the end of said screw and said disk, substantially as and for the purposes set forth.

4. A carbureter for explosive gas-engines comprising a main tubular body provided 125 with an air-intake, and an outlet, a pair of arms extending diametrically across the interior of said main body, one of the said sets of arms being provided with an internally screw-threaded hub, and the other set of 130

- said arms having a hub formed with a hole, providing a guide, a tubular gasolene-conveyer extending into the mixing chamber of said body and being provided with a screw-threaded portion screwed into said screw-threaded hub, said conveyer being provided with a plurality of perforations or holes, and a valve-seat within said conveyer; a spindle movably arranged in the hole of said one set 5 of arms, said spindle having a portion movably arranged within said conveyer and being provided with a cone-shaped end adapted to normally rest upon said valve-seat, and means connected with said spindle adapted to be actuated by suction for removing said cone-shaped end from the valve-seat and thereby 10 opening one or more of said perforations of the gasolene-conveyer.

15 7. A carbureter for explosive-gas-engines comprising a main tubular body provided with an air-intake, and an outlet, a pair of arms extending diametrically across the interior of said main body, one of said set of arms being provided with an internally screw-threaded hub, and the other set of said arms having a hub formed with a hole, providing a guide, a tubular gasolene-conveyer 20 extending into the mixing chamber of said body and being provided with a screw-threaded portion screwed into said screw-threaded hub, said conveyer being provided with a plurality of perforations or holes, and a valve-seat within said conveyer, a spindle 25 movably arranged in the hole of said one set of arms, said spindle having a portion movably arranged within said conveyer and being provided with a cone-shaped end adapted to normally rest upon said valve-seat, and means connected with said spindle adapted to be actuated by suction for removing said cone-shaped end from the valve-seat and thereby 30 opening one or more of said perforations of the gasolene-conveyer, a spindle movably arranged in the hole of said one set of arms, said spindle having a portion movably arranged within said conveyer and being provided with a cone-shaped end adapted to normally rest upon said valve-seat, a spring-controlled 35 means connected with said spindle adapted to be actuated by suction for removing said cone-shaped end from the valve-seat and thereby opening one or more of said perforations of the gasolene-conveyer.

40 8. A carbureter for explosive-gas-engines comprising a main tubular body provided with an air-intake, and an outlet, a pair of arms extending diametrically across the interior of said main body, one of said sets of arms being provided with an internally screw-threaded hub, and the other set of said arms having a hub formed with a hole providing a guide, a tubular gasolene-conveyer 45 extending into the mixing chamber of said body, and being provided with a screw-threaded portion, said conveyer being provided with a plurality of perforations or holes, a tubular member upon said conveyer, said member being provided at one end with longitudinally extending slots in alignment with said perforations of the gasolene-conveyer, a spindle movably arranged in the hole of said one set of arms, said spindle having a portion movably arranged within said conveyer and being provided with a cone-shaped end adapted to normally rest upon said valve-seat, and means connected with said spindle adapted to be actuated by suction for removing said cone-shaped end from the valve-seat and thereby 50 opening one or more of said perforations of the gasolene-conveyer.

55 9. A carbureter for explosive-gas-engines comprising a main tubular body provided with an air-intake, and an outlet, a pair of arms extending diametrically across the interior of said main body, one of said sets of arms being provided with an internally screw-threaded hub, and the other set of said arms having a hub formed with a hole providing a guide, a tubular gasolene-conveyer 60 extending into the mixing chamber of said body, and being provided with a screw-threaded portion, said conveyer being provided with a plurality of perforations or holes, a tubular member upon said conveyer, said member being provided at one end with longitudinally extending slots in alignment with said perforations of the gasolene-conveyer, a spindle movably arranged in the hole of said one set of arms, said spindle having a portion movably arranged within said conveyer and being provided with a cone-shaped end adapted to normally rest upon said valve-seat, and means connected with said spindle adapted to be actuated by suction for removing said cone-shaped end from the valve-seat and thereby 65 opening one or more of said perforations of the gasolene-conveyer.

shaped end from the valve-seat and thereby opening one or more of said perforations of the gasolene-conveyer, consisting of a disk arranged upon said spindle, an adjusting screw connected within said main body, and a spring between the end of said screw and said disk, substantially as and for the purposes set forth.

9. A carbureter for explosive-gas-engines comprising a main tubular body provided with an air-intake, and an outlet, a pair of arms extending diametrically across the interior of said main body, one of said sets of arms being provided with an internally 5 screw-threaded hub, and the other set of said arms having a hub formed with a hole providing a guide; a tubular gasolene-conveyer extending into the mixing chamber of said body, and being provided with a screw-threaded portion, said conveyer being provided with a plurality of perforations or holes, a tubular member upon said conveyer, said member being provided at one end with longitudinally extending slots in alinement 15 with said perforations of the gasolene-conveyer, a spindle movably arranged in the hole of said one set of arms, said spindle having a portion movably arranged within said conveyer and being provided with a 20 cone-shaped end adapted to normally rest upon said valve-seat, and means connected with said spindle adapted to be actuated by suction for removing said cone-shaped end from the valve-seat and thereby opening one 25 or more of said perforations of the gasolene-conveyer, combined with a throttle for regulating the degree of suction, substantially as and for the purposes set forth.

10. A carbureter for explosive-gas-engines comprising a main tubular body provided with an air-intake, and an outlet, a pair of arms extending diametrically across the interior of said main body, one of said sets of arms being provided with an internally 40 screw-threaded hub, and the other set of said arms having a hub formed with a hole providing a guide, a tubular gasolene-conveyer extending into the mixing chamber of said body, and being provided with a screw-threaded portion, said conveyer being provided with a plurality of perforations or holes, a tubular member upon said conveyer, said member being provided at one end with longitudinally extending slots in alinement 45 with said perforations of the gasolene-conveyer, a spindle movably arranged in the hole of said one set of arms, said spindle having a portion movably arranged within said conveyer and being provided with a 50 cone-shaped end adapted to normally rest upon said valve-seat, and means connected with said spindle adapted to be actuated by suction for removing said cone-shaped end from the valve-seat and thereby opening one 55 or more of said perforations of the gasolene-con-

veyer, a spindle movably arranged in the hole of said one set of arms, said spindle having a portion movably arranged within said conveyer and being provided with a cone-shaped end adapted to normally rest 60 upon said valve-seat, and a spring-controlled means connected with said spindle adapted to be actuated by suction for removing said cone-shaped end from the valve-seat and thereby opening one or more of said perforations of the gasolene-conveyer, combined with a throttle for regulating the degree of suction, substantially as and for the purposes set forth.

11. A carbureter for explosive-gas-engines comprising a main tubular body provided with an air-intake, and an outlet, a pair of arms extending diametrically across the interior of said main body, one of said sets of arms being provided with an internally 70 screw-threaded hub, and the other set of said arms having a hub formed with a hole providing a guide, a tubular gasolene-conveyer extending into the mixing chamber of said body, and being provided with a screw-threaded portion, said conveyer being provided with a plurality of perforations or holes, a tubular member upon said conveyer, said member being provided at one end with longitudinally extending slots in alinement 75 with said perforations of the gasolene-conveyer, a spindle movably arranged in the hole of said one set of arms, said spindle having a portion movably arranged within said conveyer and being provided with a 80 cone-shaped end adapted to normally rest upon said valve-seat, and means connected with said spindle adapted to be actuated by suction for removing said cone-shaped end from the valve-seat and thereby opening one 85 or more of said perforations of the gasolene-conveyer, a spindle movably arranged in the hole of said one set of arms, said spindle having a portion movably arranged within said conveyer and being provided with a 90 cone-shaped end adapted to normally rest upon said valve-seat, and means connected with said spindle adapted to be actuated by suction for removing said cone-shaped end from the valve-seat and thereby opening one 95 or more of said perforations of the gasolene-conveyer, consisting of a disk arranged upon said spindle, an adjusting screw connected with said main body, and a spring between the end of said screw and said disk, combined with a throttle for regulating the degree of suction, substantially as and for the purposes set forth.

In testimony, that I claim the invention set forth above I have hereunto set my hand 105 this 3rd day of March 1908.

THOMSON HOWELL.
